Application April 29, 1935, Serial No. 18,834

25 Claims. (Cl. 200—114)

This invention relates to fuse switches, and with regard to certain more specific features, to gang-operated fuse switches.

Among the several objects of the invention may be noted the provision of a fuse switch having a fusible element adapted to open a circuit upon overload by actually fusing and blowing out, and adapted to open the same circuit by moving out of circuit-closing position when the carrier therefor is moved out of circuit-closing position; the provision of apparatus of the class described which is adapted to effectively open a multi-phase circuit instantaneously and positively in all of the phases, from a single manually operable remotely-controlled element; and the provision of relatively simple and dependable apparatus of this class. Other objects will be in part obvious and in part pointed out hereinafter.

The invention is an improvement upon that shown in our United States Patent 1,899,915 of February 28, 1933.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a side elevation on a reduced scale showing parts in closed position;

Fig. 2 is a view similar to Fig. 1, showing parts in open position;

Fig. 3 is an enlarged fragmentary side elevation of a lower contact assembly;

Fig. 4 is a front elevation, showing a plurality of fuse switches in closed positions;

Fig. 5 is a side elevation of a fuse unit per se, parts being shown in section;

Fig. 6 is a vertical section taken on line 6—6 of Fig. 3; and,

Fig. 7 is a horizontal section taken on line 7—7 of Fig. 3.

Similar reference characters indicate corresponding parts throughout the several views of the drawings.

One of the purposes of this invention, besides providing for improved gang-operation of fuse switches, is to provide an improved fuse switch per se in which a fuse unit may set to close a circuit through a fusible link, the link opening the circuit upon overload by actual fusion thereof; and also opening the circuit upon movement of the unit to prevent undesirable arcing between

certain terminal-engaging elements on the unit and certain line terminals in the circuit. The present fuse switch retains all of the desirable characteristics inherent in actual fusing a link for disconnecting overload, with the other automatic opening features herein described.

Referring now more particularly to Fig. 4, there are shown at numerals 1 supports for carrying upper, stationary, insulator brackets 3 carrying insulators 5 for supporting brackets 53 which carry spring line terminals 7 and line connections 55 (see also Fig. 1).

Downwardly, each support 1 carries a pair of bearing blocks 9 for rotatably supporting a gang-operating shaft 11. Within the bearing blocks 9, 15 the shaft 11 is circular so that it may rotate in said blocks, and suitable collars 13 are provided for properly positioning the shaft endwise.

Outside of the bearings 9, the shaft 11 is of a polygonal (preferably square) cross section, 20 whereby operating and operated members may be readily fastened. The shaft 11 may be operated from a remote point through the provision of a clevised lever 15 clamped to the shaft and connected with a swinging link 17 by means of a 25 connecting rod 19. The link 17 is pinned to a bracket 33. At the pivot point 21 between the links 17 and 19 is also fastened a second connecting link 23 which is articulated at a pin 25 with an operating handle 27, the latter being 30 pinned at 29 to a bracket 31.

The operating lever 27 has an extension 35 wherein is an opening 37 which is adapted to align with a downward opening in the bracket 31 when the handle 27 is in the upward position 35 shown in Fig. 1. Both openings may be entered by a bolt 28 to lock the linkage and connected parts in the closed Fig. 1 position. On the other hand, when the handle 27 is down in the position shown in Fig. 2, said opening 37 aligns 40 with a second, upper opening in the bracket 31, thus providing for the insertion of the bolt 28 at this point to lock the apparatus in open position. The extension 35 of lever 27 can move from the position shown in Fig. 1 to the position 45 shown in Fig. 2 by movement through a slot 32 in the bracket 31. A corresponding slot is arranged in whatever supports the bracket 31.

Extending from one of each pair of said bearings 9 (the left-hand ones in each pair in Fig. 50 4) is a stationary extension 41 for supporting a fixed insulator 43, the latter carrying a bracket 49 which supports spring contacts 45. A line connection 47 is attached to the bracket 49.

In view of the above, it will be seen that two 55

line terminals 45 and 7 are provided, both being stationary.

As stated, the bearings 9 are in pairs. At the left of each right-hand bearing 9 of each pair 5 (Fig. 4), and clamped to the square portion of said shaft 11 is an arm 57 supporting a tilting insulator 44. From each insulator 44 extends a bracket 58 reaching in the direction of the arm 49 and carrying a socket 59. The socket 10 has side walls 61 in which are formed channels having the double notched shapes shown in Fig. 3. The purpose of the socket 59 with the notched, side channels 63 is to receive longitudinally a lower terminal-engaging element 15 65 fastened to a fuse tube 67 having latch means 69 arranged to coact with the channels 63. Spurs 71 in the bayonet latches 69 are respectively adapted to cooperate with notches 73 in 20 said channels 63 when the respective tube 67 with its terminal-engaging elements 65 is rocked or moved to the left or right. The terminal-engaging element 65 has a flat surface 79 engageable by means of the spring fingers 45 when the fuse is in the closed position shown 25 in Figs. 1 and 3. The element 65 is shown forced to the right in Fig. 3 by the reaction of springs 45. In a neutral position, the latch 69 may be adjusted so that its spurs 71 clear the notches 73 so that the tube 67 may be lifted with 30 the terminal-engaging element 65 to clear the socket 59. A shoulder 75 resting against the back 77 of the socket 59 properly positions the spurs 71 below the notches 73 when the tube 67 is in socketed position.

The fuse unit per se is described in our said United States Patent 1,899,915. It includes a leaf spring 81 attached to said terminal-engaging element 65 and normally tensioned by the pull of a fuse link 83 which is clamped to the 40 spring 81 by means of a lever 85, said lever 85 being pivoted at 86 to the spring 81 and clamping the link 83 at 87, the pulled fuse link 83 being looped over its end.

The link 83 enters the lower, open end of the 45 tube 67 and is held at the upper end in an upper metallic terminal-engaging element 88, which engages with the spring line terminal 7. This terminal-engaging element 88 carries a 50 slide stem 89 for controlling an anvil 91, the latter cooperating with a removable anvil 93 on a thumb screw 95. A spring 97 normally presses the anvil 91 toward the anvil 93 to clamp the upper end of the link 83. A stop 99 limits the 55 movement of the anvil 91 to the right so that when the thumb screw 95 is loosened to permit entry of the link 83 between the anvils, the anvil 91 will not follow the anvil 93 except for a limited distance.

Stem 89 extends exteriorly of the hollow engaging element 88 and is pinned to a lever 101, said lever in turn being pinned to an extension 103 forming a stop portion of said terminal-engaging element 88.

The bracket 58 carries an overhanging arm 105 over which is a sleet hood 107. A depending latch 109 is pivoted at 111 to said arm 105. The latch 109 has only a limited downward gravitational motion and free upward movement. Its 65 sloping surface 113 when engaged by the lever 101, permits free moving of the fuse assembly into circuit-closing position and its vertical face 115 prevents free opening and causes, in connection with the lever 101, fuse releasing functions.

As many of the units supported on frames 1 may be used, in connection with a given control shaft 11, as may be desirable. In Fig. 4, two units are shown controlled by a single control shaft and an associated linkage operated from a single lever 27. For instance, a controlled unit 15 may be used in each phase of a circuit.

The operation of the device is as follows:

Assuming that the fuse switch is closed, as shown in Figs. 1, 3, and 4, one or more of the 10 fusible links 83 may fuse, due to overload or the like. This automatically effects blowing of the respective fuse to extinguish the resulting arc 15 interiorly of the respective tube 67. This releases the spring 81 and lever 85 pivoted thereto so that the unburned portion of the link is pulled out and it is dropped as it is pulled out by opening action at 87.

On the other hand, it may be desirable to open 20 the circuit before any overload or short circuit has occurred. To do this the handle 27 is moved down, thus rotating the gang-controlled shaft 11 and rotating each one of the insulators 44 and associated arms 57. Inasmuch as the sockets 59 on the arms 57 carry the fuse tubes 67, said tubes 25 67 are rotated clockwise (Fig. 2). This causes a separation between the terminal-engaging elements 88 and 65 from the line terminals 7 and 45 respectively. However, before separating movements can proceed to a condition of complete 30 separation, the levers 101 strike the gravity latches 109, thus pulling the pins 89 so that the movable anvils 91 recede from the anvils 93, thus 35 releasing the links 83 at their upper ends, whereupon they are pulled out of the respective tubes 67 by the respective springs 81. If any arcs are 40 formed, the rapid travel of the link away from the anvils causes substantially instantaneous extinguishment. After the electric circuit has 45 been opened in the manner described, the respective 50 terminal-engaging elements 88 and 65 completely break away from the line terminals 7 and 45, so that the tubes are mechanically entirely 55 out of the circuit and are safe for removal for fuse link renewal. In coming to a final open 60 position, one of the spurs 71 positively comes in 65 behind a notch 73 so that the tube will not drop from the remainder of the apparatus. Thereafter a lineman may grip the tube, and adjust it 70 so that the spurs 71 clear the notches 73 and it 75 may be removed for refusing by turning out the wing screw 95 and fastening in a new link 83 in between the anvils 91 and 93 and then fastening it to the spring 81, at the same time tensioning the latter.

After all the tubes are re-fused, the tube units are reinserted into the sockets 59, the lever 27 is moved into its up position, thus sending all of the tubes counter-clockwise (Figs. 1 and 3). In closing the terminal-engaging elements 88 and 65 against the line contacts 7 and 45 respectively, the levers 101 slide under the gravity latches 109, temporarily lifting the same. Finally the stops 103 contact suitable portions of the 80 brackets 58 so as to effect proper final positioning. It will be noted that as each tube 67 is 85 driven to contact position, that a reaction is placed thereon by the spring contacts 45, so that the right-hand spur 71 is positioned under the 90 right-hand notch 73 (Fig. 3). Hence if the fuse 95 blows, the action engendered thereby will not project it up into contact with the arm 101.

It will be seen that among the advantages of the constructions is the fact that a circuit opening 75 may be accomplished by manual means with-

out the danger of an open arc between terminal-engaging elements and the line terminals. Any arcing is confined to a position within the upper terminal-engaging elements and to the upper

5 end of the downwardly moving link and is soon extinguished within the respective tube 67. At the same time overloads are disconnected by actual fusing of the fuse links, rather than by the less desirable process of pulling them out of 10 contact.

10 The device provides means for instantaneously disconnecting one, two, three or more phases of an electrical circuit by the operation of a single hand member at a distance from the point or 15 points of connection of the respective fuses in the circuit.

In view of the above, it will be seen that the several objects of the invention are achieved and other advantageous results attained.

20 As many changes could be made in carrying out the above constructions without departing from the scope of the invention, it is intended that all matter contained in the above description or shown in the accompanying drawings 25 shall be interpreted as illustrative and not in a limiting sense.

We claim:

1. A fuse switch comprising a support, line terminals thereon, an expulsive fuse tube assembly having terminal-engaging elements, means for moving said tube assembly to engage and disengage said elements and terminals, a fuse tensioned and electrically connecting said terminal-engaging elements, and cooperating 35 means between the tube assembly and the support for automatically releasing said fuse from one of said elements in response to movement of said terminal-engaging elements in a direction from said line terminals.

40 2. A fuse switch comprising a plurality of pairs of line terminals, expulsive fuse tubes having each a pair of terminal-engaging elements, means for simultaneously moving said tubes so as to engage and disengage said pairs of elements and terminals, fuses respectively electrically connecting the members of said pairs of terminal-engaging elements, and means for automatically removing each of said fuses from at 45 least one of said respective terminal-engaging elements in response to movement of said terminal-engaging elements from said line terminals.

50 3. A fuse switch comprising a plurality of pairs of line terminals, expulsive fuse tubes having each a pair of terminal-engaging elements, means for simultaneously moving said tubes so as to engage and disengage said pairs of elements and terminals, fuses respectively electrically connecting the members of said pairs of terminal-engaging elements, and means for automatically and substantially simultaneously removing each of said fuses from at 55 least one of said respective terminal-engaging elements in response to movement of said terminal-engaging elements from said line terminals, said means for moving all tubes being manually operable from a single remote point.

60 4. In a fuse switch, line terminals, a fuse unit having terminal-engaging elements, means for moving said fuse unit so that said terminal-engaging elements move into and out of contact with said terminal-engaging elements, a fuse connecting the terminal-engaging elements of said fuse unit, and means for automatically disconnecting said fuse from at least one of said

65 terminal-engaging elements when said fuse unit is moved so as to effect disconnection between the terminal-engaging elements and the line terminals.

5. A fuse switch comprising a plurality of pairs of line terminals, a plurality of fuse units, each fuse having at least one pair of terminal-engaging elements, means for simultaneously moving said fuse units so that said pairs of terminal-engaging elements move into and out of 10 contact with the respective pairs of line terminals, fuse links in said fuse units, and means for automatically and substantially simultaneously disconnecting each fuse from at least one terminal-engaging element in response to movements of the fuse units to disconnecting positions.

15 6. A fuse switch comprising fixed line terminals, a fuse unit comprising an expulsion tube, terminal-engaging elements associated with the 20 tube, means for mounting said tube to move said terminal-engaging elements into and out of contact with respect to said line terminals, a link in said tube, means biasing said link to tension the same and tend to withdraw it from the tube, 25 means for retaining said link in the tube against said bias, said link electrically connecting said terminal-engaging elements, and means contacting said retaining means for automatically releasing said retaining means in response to movement of the tube to disconnect the terminal-engaging 30 elements from the line terminals.

35 7. A fuse switch comprising fixed line terminals, a fuse unit comprising an expulsion tube having an opening at the lower end, terminal-engaging elements associated therewith, means for removably mounting said tube to move said terminal-engaging elements into and out of contact with respect to said line terminals, a link 40 extending out of the opening of said tube, means exteriorly of the tube biasing said link to tension the same and tend to withdraw it from the tube, means for retaining said link in the tube against said bias, said link electrically connecting said terminal-engaging elements, means contacting said retaining means for automatically releasing said retaining means in response to movement of the tube to disconnect the terminal-engaging 45 elements from the line terminals, whereby the link is drawn from the tube and projected from said opening, and means for completely disconnecting the link from the apparatus as it is projected.

50 8. A fuse switch comprising fixed line terminals, a movable carrier associated with one of said terminals, an expulsion fuse tube adapted to 55 be attached to and removed from said carrier, terminal-engaging elements on said tube, said carrier being movable to carry said terminal-engaging elements into and out of contact with said line terminals, a link electrically connecting said terminal-engaging elements, means biasing said link away from one of said terminal-engaging elements, means adapted to hold said link against movement by said biasing means, and automatic 60 means for releasing said link to be separated from one terminal-engaging element in response to carrier movement in a direction to separate said terminal-engaging elements and said line terminals, but before said engaging elements and terminals are electrically separated, whereby the 65 electrical circuit is opened before the terminal-engaging elements and line terminals are separated.

9. A fuse switch comprising fixed line terminals, a movable carrier associated with one of 70

said terminals, an expulsion fuse tube adapted to be attached to and removed from said carrier, terminal-engaging elements on said tube, said carrier being movable to carry said terminal-engaging elements into and out of contact with said line terminals, a link electrically connecting said terminal-engaging elements, means biasing said link away from one of said terminal-engaging elements, means adapted to resist said biasing means, 5 and automatic means for releasing said link to be separated from the terminal-engaging elements in response to carrier movement to separate said terminal-engaging elements and said line terminals, said automatic means comprising 10 15 spring-pressed means holding the link, a latch, and means associated with said spring-pressed means whereby upon movement of the tube to circuit-closing position, said spring-pressed means is undisturbed and whereby upon movement of 20 25 said tube toward open-circuit position, said latch effects operation of said spring-pressed means to release the fuse link.

10. In a fuse switch, line terminals, terminal-engaging elements adapted to be engaged and 25 disengaged therewith, a tube joining said terminal-engaging elements to form a cartridge, a fuse link electrically connecting said terminal-engaging elements and within said tube, means for tensioning said link and means for automatically 30 throwing said link out of electrical connection with at least one terminal-engaging element, in response to disengagement of the terminal-engaging elements from the line terminals.

11. In a fuse switch, line terminals, terminal-engaging elements adapted to be engaged and 35 disengaged therewith, a fuse unit joining said terminal-engaging elements, a fuse link electrically connecting said terminal-engaging elements and in said unit, and means for automatically disconnecting said link from the terminal-engaging elements in response to the terminal-engaging elements moving toward disengagement from the line terminals.

12. A fuse switch comprising terminal-engaging elements, enclosure means carrying said elements, a fuse link connecting said elements and in said enclosure means, means for releasing said link from one of said elements, line terminals and means for contacting the terminal-engaging 50 elements therein, and means automatically operable for releasing the link in response to said terminal-engaging elements moving from contact with the line terminals.

13. A fuse unit for closing electrical circuits comprising circuit terminal-engaging elements, a fuse link connecting said elements, and means for automatically disconnecting said link from one of said elements in response to removal of the cartridge from circuit-closing condition.

14. A fuse unit for closing electrical circuits comprising circuit terminal-engaging elements, a fuse link connecting said elements, means for tensioning said link, and means for automatically releasing said link from one of said elements in 60 response to cartridge removal from operating condition and before it is entirely removed.

15. A fuse switch comprising line terminals, terminal-engaging elements, a fuse link connecting said elements, means for tensioning said link between elements, means for releasing said link from one of said elements while the cartridge is in operating condition, said last-named means comprising a spring-pressed clamp for holding one end of said link, a tensioning means for 70 75 said link, and automatic means for releasing the

link at said spring-pressed clamp in response to movement of said cartridge from operating condition.

16. In apparatus of the class described, a pair of terminal-engaging elements, a tube connecting the same, a link passing through the tube, spring tensioning means adapted to withdraw the link from the tube, means for holding one end of the link against withdrawal, said last-named means comprising a movable anvil, spring-pressed means 10 adapted to be forced toward said anvil to hold the end of the link, line terminals, means for moving said terminal-engaging elements into and out of contact with line terminals, and means for automatically moving said spring-pressed means 15 away from said anvil to release the link in response to movement of the tube in a direction to disconnect said terminal-engaging elements from said line terminals.

17. In apparatus of the class described, a cartridge having a closed head, a link, means for holding said link in said closed head, said last-named means comprising an anvil, resilient means clamping said link against said anvil, automatic means exteriorly operable for releasing the automatic hold on said link, means for moving the cartridge into and out of said circuit-closing position, said automatic means being operable for release only when said cartridge is moved in the direction of its open-circuit position.

18. A switch comprising line terminals, terminal-engaging elements, conducting means connecting said elements, means for tensioning said conducting means and means for automatically releasing the conducting means from one of said terminal-engaging elements, said automatic means being effective only when the terminal-engaging elements are moved in a direction away from said line terminal.

19. A switch comprising line terminals, terminal-engaging elements, an enclosure having at least one opening and upon which said engaging elements are mounted, a conductor joining said engaging elements and positioned in said enclosure, means tensioning the conductor and means for automatically releasing the conductor while electrified from one of the engaging elements when the terminal-engaging elements are moved in a direction to separate them from the line terminals.

20. A fuse switch comprising terminal-engaging elements, means joining said elements forming an enclosure, a fuse link in said enclosure and joining said elements, whereby a movable fuse unit is formed, line terminals, means mounting said fuse unit for moving said terminal-engaging elements into and out of contact with the line terminals, means for maintaining a connection between the link and the terminal-engaging elements when the unit is moved to contact the terminal-engaging elements with the line terminals but automatically to disconnect the link from at least one terminal-engaging element in response to separation of the terminal-engaging elements from the line terminals, 55 whereby after circuit closure, the circuit can only be reopened by way of said fuse link either by blowing of the link or by initial movement of fuse unit.

21. A fuse switch comprising line terminals, terminal-engaging elements, means for moving said terminal-engaging elements into and out of contact with the line terminals, a fusible link electrically joining said terminal-engaging elements, means for electrically disconnecting said

link from said engaging elements in response to movement of the engaging elements away from the line terminals but permitting the link to fuse upon overload without separation of the engaging elements from the line terminals.

22. A fuse switch comprising a plurality of pairs of line terminals, a plurality of pairs of corresponding terminal-engaging elements, means for moving said pairs of terminal-engaging elements into and out of contact with the respective pairs of line terminals, fusible links respectively electrically joining the members of said pairs of terminal-engaging elements, means for substantially simultaneously electrically disconnecting all of said links from said engaging elements in response to movement of the engaging elements away from the line terminals but permitting the links to fuse upon overload without separation of the engaging elements from the line terminals.

23. A fuse switch comprising line terminals, a pivoted socket, an expulsion fuse cartridge including means applicable into said socket and portions engageable with said line terminals, and locking means between the means in the socket and said socket adapted automatically to lock upon movement of said portions into engagement with the line terminals, but to readily unlock under manipulations adapted to remove the said means from the socket.

24. A fuse switch comprising line terminals, one of which is resilient, a pivoted socket, an expulsion fuse cartridge including terminal engaging elements, part of said cartridge being applicable to said socket, and locking means between the part of the cartridge in the socket and said socket adapted automatically to lock upon contact between the terminal engaging elements and the line terminals, but to readily unlock under manipulations adapted to remove the cartridge from the socket.

25. A fuse switch comprising line terminals one of which is resilient, a pivoted socket electrically associated with the resilient terminal, an expulsion fuse cartridge including terminal engaging elements, one of said terminal engaging elements being applicable to said resilient socket, and locking means between the terminal engaging element in the socket and said socket adapted automatically to lock upon movement of the socket toward the resilient terminal and upon contact between the terminal engaging element in the socket and the resilient line terminal, but to readily unlock under manipulations adapted to remove the cartridge from the socket when the socket is moved away from the resilient terminal.

CLAUD L. MATTHEWS.
THEODORE BIRKENMAIER.
